Puff
Mincers
(Pettet's Patent)

The above is a copy of the above Patent and making part of the same
containing a description with some of the uses of the said Puff Mincers himself of his in-
vention in the mode of constructing wheel for cars and locomotive engines to
be used on Railways.

To all whom it may concern. Be it known that I, High Mincers of the City
of Baltimore in the State of Maryland and Burgess have invented an improvement
in mode of constructing wheel for cars and locomotive engines to be used on Railways
and that the following is a full and exact description thereof.

There are, already, to exhibit the difference between my improved wheel and those
which have been heretofore employed. I will briefly point out the manner in which
wheel for the purpose have been most commonly made, not intending however as it
is unnecessary for the purpose in view to describe all the places which have been adopted,
but such wheel have been made wholly or nearly of cast iron, the face or head of them
being cast within a chill consisting of a thick rim or hoop of iron wheel forms a
part of the mould. 2d. The wheels have been cast without being chilled and often
incorporated with wrought iron which then forms the face and flange of the wheel.
3d. Another mode which has been made to receive two or three spokes, connected in
order, by which was bridged with a tie of wrought iron. 4th. The last which
consists of cast iron with spikes of wrought iron and a rim of wrought iron cast iron
braced with wrought iron. These plans have each their respective advantages
and disadvantages but neither of them has fully answered the purpose for which
it has been adopted. The wrought iron hoop or rim of the cast iron wheels have
gradually become broken, the wooden spikes and felloes have passed the iron
into the other and the timber caused to bind them, and cast wheels are going
out of use. Secondly, these defects are often incident to some of the wheels
which are of my improvement. My wheel consists essentially of three parts, namely
the iron wheel, the iron spikes, and one of which are of wood and a rim of
iron formed in a way to be perfectly described surrounding the cast iron wheel.
A hoop or band of wrought iron surrounding the wood and forming the face or head

844-74

of the wheel. The iron wheel is made in some respects like that just noticed but the face is not chilled nor has it the same form with the chilled face. It should be made of the same iron as on the rim with the wrought tire which is to surround and form the tear of the wheel say four inches. The face of the cast iron may be cylindrical, that is to say the part of its width but it must in this case have a fillet or edge projecting upon each side of it say to the height and of the thickness of half an inch which will then give to it the appearance of a wheel with a double flange having a cylindrical tread of four inches in width. Instead of making the face in this form, it is better sometimes to give to it a regular declination from each edge towards the center. A section of the rim transversely would then be somewhat in the form of the letter V, but with the angle obtuse. The declination will be sufficient if the diameter at the center of the rim is one inch less than that of the sides or edges. Other forms may be given to the face of this rim by which the object in view may be attained namely that of enclosing the wooden rim in its place without allowing it to move out on either side. A rim of wood is to be placed around this which may consist of any convenient number of pieces fitted to each other and to the face of the wheel. The purpose of the wood is to crop the rim of the wheel running parallel with its axis. These pieces may be fitted to the face of the wheel with great facility by driving them into a large hoop running as a choker in a lattice by which means they may be turned to the form required, they may then be fastened on to the rim by wood screws or other wire and turned therein to receive the iron hoop or tire. The best thickness of this rim will be from two to four inches. The hoop or tire of wrought iron is to be made in the usual form turned truly and shaped on over the wooden rim when expanded by heating it as highly as may be done without burning the wood. Bolts are then to be passed through the wrought iron, the wood and the cast iron rim and secured by nuts to confine the whole together. The hub or nave in a wheel thus made may be cast entire instead of having three divisions or openings which are necessary in the chilled wheel to allow for contraction. Although I have described the spokes and rim as being of cast iron, either or both of them may be of wrought iron but it would be more easily contrived offering any adequate advantages, those of cast iron being perfectly safe in this mode of construction. It will be necessary for

178477 X

421

caused that the wood thus placed between two lodges of iron has an extent of bearing surface which will effectually prevent its being condensed by the force to which it is subjected, whilst by its elasticity, it will tend to preserve both the road and the vehicles passing over it. If perfectly dried when put on which may be done by artificial heat the wood will never shrink but on the contrary will expand and render all the parts more firm. Such a wheel will have less tendency than any other where wood is employed to get out of truth and should recutting become necessary it may be done more effectually than with any other. The dimensions of most of the parts of such a wheel need not differ greatly from those of the east iron wheels with wheelbar rows, but to fit them more vary according to their diameter and the load they are to sustain, the following is a good proportion for wheels of three feet in diameter intended for a carrying three tons. East iron interior wheel 29 inches diameter, hub 7 inches long, by 6 inches diameter spokes 12 in number $\frac{3}{8}$ of an inch thick, and $\frac{3}{4}$ or 4 inches broad, rim 5 inches broad, by $\frac{3}{8}$ of an inch thick; iron rim 2 $\frac{1}{2}$ inches thick, 5 inches deep measuring across the rim, wrought iron tire $\frac{1}{2}$ inch thick 5 inches broad flange $\frac{1}{4}$ inch deep, 1 inch thick. Although I have described the rim of wood as placed with its grain crossing the rim of the wheel and am fully convinced that this is the best manner of placing it, yet it will answer the purpose to a considerable extent when running in the direction of the rim, and I do not intend therefore to limit myself in this respect as what I claim as my invention is the interposing a rim or belt of wood between an iron interior of a wheel or wrought iron rim and a wrought iron tire in a tire, and securing the whole together in the manner and for the purposes herein after set forth.
